CLAIM

We claim the ornamental design for a battery, as shown and described.

DESCRIPTION

FIG. 1 is a perspective view of a battery according to an embodiment of the invention.

FIG. 2 is a first side view of the battery shown in FIG. 1.

FIG. 3 is a second side view of the battery shown in FIG. 1.

FIG. 4 is a third side view of the battery shown in FIG. 1.

FIG. 5 is a fourth side view of the battery shown in FIG. 1.

FIG. 6 is a fifth side view of the battery shown in FIG. 1; and,

FIG. 7 is a sixth side view of the battery shown in FIG. 1. Elements shown in broken lines are included for the purpose of showing environment and unclaimed portions of the battery charger and form no part of the claimed design.
